(57) **CLAIM**

The ornamental design for a jewelry article, as shown and described.

DESCRIPTION

FIG. 1 is a top perspective view of a first embodiment of a jewelry article showing my new design;

FIG. 2 is another top perspective view thereof;

FIG. 3 is a side view thereof;

FIG. 4 is another side view thereof;

FIG. 5 is a top plan view thereof;

FIG. 6 is a bottom plan view thereof;

FIG. 7 is a top perspective view of a second embodiment of a jewelry article showing my new design;

FIG. 8 is another top perspective view thereof;

FIG. 9 is a side view thereof;

FIG. 10 is another side view thereof;

FIG. 11 is a top plan view thereof;

FIG. 12 is a bottom plan view thereof;

FIG. 13 is a top perspective view of a third embodiment of a jewelry article showing my new design;

FIG. 14 is a top perspective view thereof;

FIG. 15 is a side view thereof;

FIG. 16 is another side view thereof;

FIG. 17 is another side view thereof;

FIG. 18 is a top plan view thereof;

FIG. 19 is a bottom plan view thereof;
FIG. 20 is a top perspective view of a fourth embodiment of a jewelry article showing my new design;
FIG. 21 is another top perspective view thereof;
FIG. 22 is a side view thereof;
FIG. 23 is another side view thereof;
FIG. 24 is another side view thereof;
FIG. 25 is a top plan view thereof;
FIG. 26 is a bottom plan view thereof;
FIG. 27 is a top perspective view of a fifth embodiment of a jewelry article showing my new design;
FIG. 28 is a second top perspective view thereof;
FIG. 29 is a side view thereof;
FIG. 30 is another side view thereof;
FIG. 31 is a top plan view thereof;
FIG. 32 is a bottom plan view thereof;
FIG. 33 is a top perspective view of a sixth embodiment of a jewelry article showing my new design;

FIG. 34 is another top perspective view thereof;
FIG. 35 is a side view thereof;
FIG. 36 is another side view thereof;
FIG. 37 is a top plan view thereof;
FIG. 38 is a bottom plan view thereof;
FIG. 39 is a top perspective view of a seventh embodiment of a jewelry article showing my new design;
FIG. 40 is another top perspective view thereof;
FIG. 41 is a side view thereof;
FIG. 42 is another side view thereof;
FIG. 43 is a top plan view thereof; and,
FIG. 44 is a bottom plan view thereof.
The dash-dot lines shown in FIGS. 1-2, 7-8, 13-14, 20-21, 27-28, 33-34, and 39-40 indicate boundaries between the claimed design and unclaimed subject matter. The dashed lines shown in FIGS. 1 through 44 illustrate environmental subject matter only and form no part of the claimed design.
